CONTROL DEVICE

Bertil L. Johnson, Chaska, Minn., assignor to
 Minneapolis-Honeywell Regulator Company,
 Minneapolis, Minn., a corporation of Delaware

Application July 6, 1948, Serial No. 37,273

2 Claims. (Cl. 200—83)

1

This invention relates to condition responsive control devices and more particularly to means for adjusting such devices to operate at desired condition values.

One object of the invention is to provide a condition responsive control device in which the cut-in and cut-out points may be relatively varied.

Another object is to provide a device in which a snap switch is actuated in response to changes in variable condition and having two springs that may be adjusted to determine the condition values at which the switch is opened and closed.

A more specific object is to provide a pressure actuated switch in which the pressure is opposed by different springs or combination of springs when the switch is moved to closed and to open positions.

Other objects will be apparent from the detailed specification and claims, and from the drawing in which,

Figure 1 is an elevation, partly in section, of a pressure actuated switching device.

Figure 2 is a fragmentary sectional view taken on line 2—2 of Figure 1.

Figure 3 is a fragmentary view illustrating a modified form of the invention, and

Figure 4 is an elevation, partly in section, illustrating another modified form of the invention.

The pressure switch illustrated in Figure 1 is provided with a frame 10 that includes a base plate 11. The plate 11 has a cup-shaped portion 12 formed therein which serves as the rigid element of a pressure responsive chamber. A thin cup-shaped metal diaphragm 13 is secured over the top of the cup-shaped portion 12 of the plate 11 and serves as the movable element of a pressure chamber. An internally threaded pressure connection 15 is attached to the underside of the pressure chamber. The frame 10 also includes a bracket 17 to which is secured a snap switch 18 having the usual push button type of actuator 19. Snap switch 18 may be of the type disclosed in the patent to Albert E. Baak, 2,318,734, but the only requirement of this switch as far as the present disclosure is concerned is that the switch be operated to one of its operative positions at one position of the button 19 and to the other of its operative positions at a different position of the button 19.

The upper surface of the diaphragm 13 engages a plate 21 having upwardly extending projections 22 that engage a switch actuating lever 24. The lever 24 is pivoted on a pin 25 of the frame bracket 17. A spring strip 27 has its right-hand

end secured to the lever 24 adjacent the pivot 25 and its left-hand end engages the under side of the head of a screw 28 which is adjustably secured in the lever 24. An intermediate portion 5 of the strip 27 is adapted to engage the switch actuating button 19. By adjusting the screw 28 it is possible to determine the position of the diaphragm 13 at which the spring strip 27 will actuate the switch. Also, on excessive pressure the strip 27 is adapted to leave the head of the screw 28 to act as a strain release. Upward movement of the lever 24 is resisted by a pair of springs as will be hereinafter described. An increase in pressure will raise the lever 24 and the spring strip 27 to actuate the switch in one direction. Likewise, a decrease in pressure will result in the lever 24 being moved downwardly to actuate the switch in the opposite direction.

A post 30 is adjustably mounted in the frame 10 by a screw-threaded portion 31 and is secured by a lock-nut 32. The post 30 carries a main spring 34 and a pick-up spring 35 both of which are adapted to oppose upward movement of the lever 24. The lower end of the spring 34 is carried by a spring retaining cup 36 which has a centrally located aperture to accommodate the post 30. The left-hand end of the lever 24 engages the under side of the cup 36. On variations in pressure the lever 24 raises and lowers the cup 36 on the post 30 to position the lower end of the spring 34. A nut 37 which is screw-threaded on the upper end of the post 30 serves to adjustably position the spring retaining cup 38 to determine the position of the upper end of the spring 34. By adjusting the nut 37 it is possible to adjust the force exerted by the spring 34 on the lever 24 when the strip 27 engages pin 19 to actuate switch 18.

The pick-up spring 35 is confined between 40 spring retaining cups 40 and 41. Downward movement of the lower cup 40 is limited by a shoulder 43 on the post 30. The position of the upper cup 41 is determined by an I-shaped member 45 that is located in a slot in the post 30. See Figure 2. The position of the member 45 and therefore the position of the upper end of the spring 35 is determined by a nut 46 which is in threaded engagement with the post 30. It will be seen that the member 45 has its central portion 45 extending through the central apertures in the nut 37 and the spring retaining cup 38. The member 45 may be assembled to pass through the nut 37 and cup 38 prior to assembly on the post 30. This is accomplished by bending one or more 55 of the laterally extending ears of the member 45.

The post 30 is adjusted in the frame 10 and the screw 28 is adjusted in the lever 24 to position the strip 27 relative to the lever 24 so that when the spring retaining cup 36 engages the retaining cup 40, the switch actuating button 19 will be intermediate the positions at which the switch is actuated to its two operative positions. When the pressure is increased and the lever 24 is moved upwardly from the position shown in Figure 1, the switch will not be actuated from its original position until the lever 24, through the cup 36, has raised the cup 40 and the lower end of the spring 35 from the position shown. Thus, the pressure must overcome the forces of both the springs 34 and 35 before the switch will be actuated. On the other hand, when the pressure is reduced the switch will not be actuated to its original position until the lever 24 has lowered the spring retaining cup 36 to a position out of engagement with the cup 40, and hence only the force of the spring 34 has any effect on the pressure at which the switch 18 will be actuated to its original position.

The spring 34 may thus be adjusted to vary both the cut-in and cut-out pressures of the switch, whereas the pick-up spring 35 may be adjusted to determine the operating differential of the switch. By providing a mechanism in which the differential adjusting or pick-up spring 35 is located concentrically and inside the spring 34, a very compact structure is provided and one in which the parts are reduced to a minimum.

The bracket 17 may be provided with an extension 49 on which suitable indicia may be placed to indicate the pressure settings of the spring 34. Or, alternatively, the extension 49 may merely contain a suitable legend indicating the direction in which the nut 37 should be moved to raise or lower the control pressure.

Figure 3 shows a modification of the spring arrangement that differs in some respects from that shown in Figure 1. It will be understood that the pressure chamber, switch and mechanical linkage may be the same as shown in Figure 1. A post 50 is secured to the plate 11 of the frame 10 and carries a main spring 53 and a pick-up spring 54 concentrically thereon. The spring 53 is provided with retaining cups 55 and 56, the former of which is adapted to be engaged by the switch actuating lever 24. The post 50 has an extension 57 which is also screw-threaded to carry a nut 58 which serves as an adjustable abutment for the upper spring retaining cup 56. The inner spring 54 bears against a spring retaining cup 60 which is adapted to engage a shoulder 61 on the post 50 to determine its lower limit of travel. The upper end of the spring 54 engages a cup 63 which is adjustably positioned by a shoulder 64 formed by the bottom end of the extension 57 of the post 50. A collar 66 is slideable on the post 50 to transmit movement from the lower spring retaining cup 55 to the cup 60 which supports the lower end of the spring 54.

With the lever 24 in the position shown and the spring retaining cup 60 in engagement with the shoulder 61, the switch is intermediate its two operative positions. If the switch has not yet been actuated in the direction caused by pressure increase, it will be necessary to raise the lever 24 against a combined force of the springs 53 and 54 in order to actuate the switch. On the other hand, if the switch has not yet been actuated in a direction corresponding to a decrease in pressure, then the lever 24 will be lowered to actuate the switch only when the pressure is re-

duced to a value at which the force of the spring 53, acting along, will balance the pressure.

To adjust the pressure at which the switch will be actuated on pressure increase the post extension 57 is rotated on the post 50 to determine the position of the upper end of the spring 54, and the nut 58 is adjusted on the post extension 57 to determine the position of the upper end of the spring 53. This pressure value depends on the adjustment of both springs. To select the pressure value at which the switch will be actuated on pressure decrease, only the spring 53 need be adjusted by rotating the nut 58 on the extension 57. This modification is similar to that shown in Figure 1 with the exception of the mechanism by which the inner and outer springs are adjusted.

Figure 4 shows another spring arrangement, and one in which the cut-in and cut-out values may be independently adjusted. Here also the pressure chamber, mechanical linkage and switch may be identical to the arrangement shown in Figure 1 and their description will not be repeated. A post 70 is suitably secured to the plate 11 and carries springs 72 and 73 concentrically with respect thereto. The lower spring 72 is confined between a lower retaining cup 75 and an upper retaining cup 76. The cup 76 is adjustable on a sleeve 78, which is axially slideable on the post 70, by a nut 79. The lower end of the sleeve 78 is limited in downward movement by a shoulder 81 on the post 70. The lower cup 75 engages the bottom of the sleeve 78 when it is raised upwardly by the lever 24 in response to pressure increase.

The lower end of the spring 73 is confined by a cup 82 and is positioned by the upper end of the sleeve 78. A nut 84 is adjustable on the post 70 to position a cup 85 to adjust the upper end of the spring 73.

It is necessary to move the lever 24 above the position in which the cup 75 engages the sleeve 78 in order to actuate the switch to one of its operative positions and it is likewise necessary to lower the lever 24 below that position to move the switch to the other operative position. As the pressure increases from the position shown in Figure 4 the lever 24 will be raised to compress the spring 72 to the extent permitted by the sleeve 78, but no switching operation will take place. When the lever 24 is raised above this position spring 72 is not further compressed, but rather the sleeve 78 together with the spring 72 are raised on the post 70. The pressure required to cause this movement is determined solely by the spring 73, and hence the pressure value at which the switch is actuated in response to pressure increase is determined solely by adjustment of the nut 84 which determines the position of the upper end of the spring 73.

If the pressure is reduced, the lever 24 will lower the sleeve 78 until the sleeve abuts the shoulder 81, rendering the spring 73 inoperative. To cause switch actuation it is then necessary to further reduce the pressure until the spring 72 overcomes the upward force on the lever 24 and permits slight separation of the cup 75 from the sleeve 78. Hence it will be seen that only the downward force of the spring 72 as determined by the adjusted position of the nut 79 on the sleeve 78 determines the pressure at which the switch will be actuated in response to a reduction in pressure.

It will be seen that the pressure values at which the switch may be actuated to operative posi-

tion are independently adjusted by means of the nuts 79 and 84. While not illustrated, it will be apparent that pointers could be arranged to be moved in accordance with the adjusted positions of these two nuts and that these pointers might be arranged to cooperate with suitable indicia to indicate directly the pressure values at which the switch will be actuated. While the various features of the invention have been illustrated in connection with a pressure responsive device it is evident that any other condition which would produce the same effect as the pressure chamber might be substituted therefor. Also, while the switching device has been assumed to be an electric snap switch, it is evident that any other switching device having similar operating characteristics could be substituted. For example, a control valve operated with a snap action between on and off positions could be employed. Also a mercury switch having an operating angle differential might be actuated in the same manner as the snap switch described. The scope of the invention is to be determined only by the appended claims.

I claim:

1. In a control device, a frame, a member movable in said frame, a condition responsive element operatively connected to said member and biasing said member in one direction with a force depending on condition value, a switch carried by said frame and operated by said member, said switch being operative to make or break a circuit on movement of said member through a predetermined range, a post secured to said frame, a sleeve slidable on said post, a stop for limiting movement of said sleeve, a first spring having one portion secured to said sleeve and another portion acting on said member, said sleeve also serving as a stop to limit relative movement of

the two portions of said first spring, a second spring secured at one portion to said post and having another portion engaging said sleeve and biasing said sleeve against said stop.

5 2. In a control device, a frame, a member movable in said frame, a condition responsive element operatively connected to said member and biasing said member in one direction with a force depending on condition value, a switch carried by said frame and operated by said member, said switch being operative to make or break a circuit on movement of said member through a predetermined range, a post secured to said frame, a sleeve slidable on said post, a stop for limiting movement of said sleeve, a first spring having one portion secured to said sleeve and another portion acting on said member, said sleeve also serving as a stop to limit relative movement of the two portions of said first spring, a second spring secured at one portion to said post and having another portion engaging said sleeve and biasing said sleeve against said stop, and adjusting means for adjusting the bias applied by said first spring to said member and by said second spring to said sleeve.
